(57) **CLAIM**

The ornamental design for an extractor hammer, as shown and described.

DESCRIPTION

FIG. 1 is a perspective view of an extractor hammer in accordance with the new design;

FIG. 2 is a right side view of the extractor hammer of FIG. 1;

FIG. 3 is a left side view of the extractor hammer of FIG. 1;

FIG. 4 is a front view of the extractor hammer of FIG. 1;

FIG. 5 is a rear view of the extractor hammer of FIG. 1;

FIG. 6 is a top plan view of the extractor hammer of FIG. 1; and,

FIG. 7 is a bottom plan view of the extractor hammer of FIG. 1.

The broken lines in FIGS. 1-7 illustrate portions of the extractor hammer which form no part of the claimed design.
